UNITED STATES PATENT OFFICE

OLAV ESKIL JORGENSEN, OF COPENHAGEN, DENMARK.

INTERNAL-COMBUSTION ENGINE.

1,269,454.

Specification of Letters Patent. Patented June 11, 1918.

Application filed July 11, 1916. Serial No. 108,543.

To all whom it may concern:

Be it known that I, OLAV ESKIL JORGENSEN, a subject of the King of Denmark, and residing at 16 Fredericiagade, Copenhagen, K, Denmark, have invented certain new and useful Improvements in and Relating to Internal-Combustion Engines, of which the following is a specification.

This invention relates to water circulating gear for supplying cooling water to an internal combustion engine piston.

To form pipe connections which allow water to circulate through the moving piston of an internal combustion engine it is a common practice to provide an inlet and outlet tube on the piston and to arrange for these tubes to telescope in and out of external tubes which are carried upon a stationary portion of the engine, at the moving joint packing glands of some kind being provided to prevent the escape of water. It has been found, however, that such glands speedily become worn and leak, particularly in marine engines where salt water is used for circulation purposes.

In another form of gear which has been employed in vertical engines, three telescoping tubes are used which fit freely one within the other, the intermediate tube being fastened to and moving with the piston, and the inlet water being discharged as a strong jet from the inner stationary tube which projects beyond the outer stationary tube into the mouth of the moving tube. The jet in this case must be sufficiently powerful to overcome the resistance of the downcoming water in the moving tube which will be very considerable. Such an arrangement, necessitates the use of high pressure water for the circulating system to overcome the inertia of the water which is continually changing its direction of movement in the moving tube.

The object of the present invention is to overcome the disadvantages of the foregoing arrangements and to provide an improved form of water circulating gear.

The invention consists in a water circulating gear for a vertical internal combustion engine piston having a projecting tube working easily over an internal stationary pipe conveying circulating water, in which said tube and pipe form a telescoping conduit through which the supply only is con-

ducted at a moderate pressure, and any water passing through the sliding joint is led away by a further encircling pipe without having reached the piston.

The invention further consists in a water circulating gear for an internal combustion engine piston in which two tubes carried by the piston and positioned one within the other serve for the water inlet and outlet respectively, a fixed pipe which supplies the water telescoping within the inner tube and the outer tube telescoping within another fixed pipe which surrounds the supply pipe and leads away the outlet water.

The invention further consists in a method of connecting a circulating water service to the piston of a vertical internal combustion engine in which the inlet pipe is provided with an easily fitting telescoping joint and the leakage from said joint is entrained by the outlet water which forms a downwardly flowing curtain surrounding the inlet pipe.

The invention further consists in a water circulating gear comprising a fixed upwardly extending inlet pipe, a tube extending from the piston telescoping easily over said pipe, a passage from said tube reaching to the upper portion of the hollow piston, a second larger tube enveloping the last and forming an annular passage communicating with the lower portion of the piston interior, said two tubes communicating freely at their lower ends, an external fixed pipe wherein said larger tube loosely telescopes, a liquid supply connection to said inner fixed pipe and a free delivery connection to the external pipe.

The invention also consists in an improved water circulating gear for an internal combustion engine piston as hereinafter described.

Referring now to the accompanying drawing which shows by way of example one way of carrying the invention into effect in a vertical single-acting internal combustion engine:

Attached to the moving piston 1 of the engine are two tubes, one within the other; the outer one *f* is fastened to the cover 2, forming the bottom of the piston, by means of a flange *f'*. The internal one *e* has its top end fastened tightly in the cover 2 and is secured at the bottom end by means of

2
a cone-shaped nut *g* in which are holes *h*. *g*' is a check nut for securely locking the nut *g*.

The internal pipe *e* is continued by means 5 of a passage *i* to the upper portion of the hollow piston, the latter part of the passage being cut in the piston rod. The annular space between the internal and the external pipe is continued by means of a passage 10 *k* through the bottom of the piston.

a is a pipe through which cooling water is led under moderate pressure to a straight upwardly extending pipe *b* which has at its lower end a flange *m* which is tightened 15 by means of a separate flange *q* against a heavy elastic packing *c* in a recess in the casing *n* in such a way that the pipe *b* can move slightly from the perpendicular to allow for inaccurate alinement and to avoid 20 undue wear, without becoming leaky at the joints.

At the top end of the pipe *a* there is a bush *d* which may be formed of lignum vitæ or other suitable material and which is an 25 easy fit inside the tube *e*.

From the casing *n* there is continued upwardly a pipe *o* which is open at the top and may be provided with a basin *o'* having an inturned rim. At the lower end of *o* there 30 is a discharge pipe *p* for the water. The discharge pipe should be of ample area and free from obstructions.—

The arrangement operates as follows:—

Water flowing under moderate pressure 35 through *a*, *b* and a variable portion of the tube *e* will pass through the passage *i* to the piston and down through the passage *k* and the annular space between *e* and *f*. At the same time a portion will also leak 40 by the bush *d* down through the internal pipe *e* and become mixed up with the main body of water which is passing down the annular space to the discharge *p*.

Any water that leaks from the telescoping 45 joint of the supply pipe will be already moving in a downward direction and as the outlet water when surrounding the same also forms a downwardly moving curtain there will be no tendency for any water to escape 50 from the circulating service so long as the outlet passage is made free and of sufficient area.

By the employment of this invention the use of packing glands for the moving joints 55 of a circulating water gear is entirely obviated and it is also possible to work with considerable clearance between the moving parts without incurring any external leakage of circulating water with the attendant 60 drawbacks. It will be clear that modifications may be made in the arrangement and the manner of carrying the invention into effect, without in any way departing from the spirit of the same.

Having now described my invention, what

I claim as new and desire to secure by Letters Patent is:—

1. In combination in a water circulating gear for a vertical engine piston an upwardly extending inlet pipe, flexibly secured 70 at its lower end, a tube extending from the piston telescoping easily over said pipe, an enlarged head to said pipe fitting nicely within said tube and means for leading the water away from said piston. 76

2. In combination in a water circulating gear for a vertical engine piston a pipe secured below and extending upward to lead water to said piston, a tube depending from the piston telescoping easily over said pipe, 80 a passage from said tube reaching to the upper portion of the hollow piston, and a second encircling tube depending from said piston for leading water from the lower portion thereof in a downward stream enveloping said pipe and tube so as to entrain any water leaking past the telescoping joint. 85

3. In combination in a water circulating gear for a vertical engine piston an inlet 90 pipe secured below and extending upward, a tube depending from the piston telescoping easily over said pipe, a second larger tube depending from the piston and enveloping the last to form an annular passage for the 95 discharge water, and an external fixed pipe wherein said larger tube loosely telescopes.

4. In combination in a water circulating gear for a vertical engine piston an upwardly extending inlet pipe flexibly secured 100 at its lower end, a tube extending from the piston telescoping easily over said pipe, a second larger tube enveloping the last and connected thereto to form an annular passage having a free outlet for the discharge 105 water, at its lower extremity, and an external fixed pipe wherein said larger tube loosely telescopes.

5. In combination in a water circulating gear for a vertical engine piston a fixed 110 upwardly extending inlet pipe, a tube extending from the piston telescoping easily over said pipe, a passage from said tube reaching to the upper portion of the hollow piston, a second larger tube enveloping the 115 last and forming an annular passage communicating with the lower portion of the piston interior, said two tubes being connected and said annulus having a free outlet at the lower end, an external fixed pipe 120 wherein said larger tube loosely telescopes, a liquid supply connection to said inner fixed pipe and a free delivery connection to the external pipe.

6. In combination in a water circulating 125 gear for a vertical engine piston an upwardly extending inlet pipe flexibly secured at its lower end, a tube extending from the piston telescoping easily over said pipe, an enlarged head to said pipe fitting nicely 130

within said tube, a passage from said tube reaching to the upper portion of the hollow piston, a second larger tube enveloping the last and forming an annular passage communicating with the lower portion of the piston interior, said two tubes communicating freely at their lower ends, an external

fixed pipe wherein said larger tube loosely telescopes, a liquid supply connection to said inner fixed pipe and a free delivery connection to the external pipe.

In testimony whereof I have signed my name to this specification.

OLAV ESKIL JORGENSEN.
